UNITED STATES PATENT OFFICE.

ERASTUS EDWIN WINKLEY, OF LYNN, MASSACHUSETTS.

SOLE-MACHINE.

1,101,603.

Specification of Letters Patent. Patented June 30, 1914.

Application filed December 3, 1900, Serial No. 38,450. Renewed September 12, 1911. Serial No. 648,881.

To all whom it may concern:

Be it known that I, ERASTUS EDWIN WINKLEY, a citizen of the United States, residing at Lynn, in the county of Essex and State of Massachusetts, have invented 5 certain new and useful Improvements in Sole-Machines; and I do hereby declare the following to be a full, clear, and exact description of the invention, such as will enable others skilled in the art to which it 10 appertains to make and use the same.

The present invention relates to sole machines and more particularly to machines for operating upon the soles of lasted shoes.

15 The primary object of my invention is to provide an improved means for feeding the work to the trimming and nailing devices of machines for attaching the heel seat of a shoe sole to the lasted upper and 20 insole and rounding or trimming the projecting edge to conform substantially to the shape of the last. As to certain features, however, my invention is not limited to such 25 machines as these features might be embodied advantageously in mechanism for feeding the work in other shoe machines which are adapted to operate upon a lasted shoe as shoe sewing, pegging, tacking, rounding or channelling machines.

30 The type of machine to which my invention is particularly designed to be applied is well illustrated and described in the patent to G. H. Gifford, No. 579,144, dated March 23, 1897, the immediate object of the 35 invention being to obviate the objectionable features of the feeding mechanism of the patented machine. As will be readily understood from the patent drawings and specification, in the patented machine, the lasted 40 shoe is rotatably supported on a last pin at the upper end of a post freely movable toward and from a gage and also freely movable laterally of the gage. For feeding the work a four-motion feed pawl which 45 engages the bottom of the sole is provided. This feeding pawl advances the work intermittently between successive actuations of the trimming knife and nailing device, the shoe being rotated on the last pin and the 50 post being moved laterally by the operator to keep the shoe in contact with the gage.

In the practical operation of the machine it is found that when the shoe is turned and moved laterally the throat of the nailing 55 device, the trimming knife, and the feed pawl

constitute three separate points about which the work can turn, and that the work is turned sometimes about one point and sometimes about another according to the time in the operation of the machine at which 60 the operator attempts to move the shoe. As a result the edge of the heel seat is often trimmed unevenly.

To obviate these defects my invention contemplates providing a jack for supporting the lasted shoe and suitable mechanisms for actuating the jack to feed the edge of the heel seat to the trimming knife so that the heel seat is trimmed evenly to conform to the shape of the last. The jack and the mechanism for actuating it which I have devised afford a simple and efficient means for obviating the objections above noted. It is to be understood, however, that the jack and 65 its actuating mechanism might be constructed in many different ways without departing from the essential features of my invention which are not limited to details of construction. It is also to be understood that while the immediate object of my invention is to improve the feeding mechanism of a heel seat nailing and trimming machine, certain features of the jack and its actuating mechanism are equally applicable to other machines for operating upon lasted shoes 70 and as to such features my invention is not limited to any particular type of machine.

75 My invention also has for its object to improve the construction, arrangement and operation of various parts of a heel seat 80 nailing and trimming machine.

With the above objects in view my invention consists in the devices, combinations and arrangements hereinafter described and claimed.

85 A preferred form of my invention is illustrated in the accompanying drawings in which—

90 Figure 1 is a view in side elevation of a heel seat nailing and trimming machine 100 embodying the same; Fig. 2 is a view in front elevation of the head of the machine, the jack and the lasted shoe supported thereon, shown in Fig. 1, being omitted; Fig. 3 is a cross-sectional view of the head of the 105 machine on the line 3—3 of Fig. 1; Fig. 4 is a view in elevation of the opposite side of the head of the machine to that shown in Fig. 1; Fig. 5 is a sectional plan view on the line 5—5 of Fig. 4; Fig. 6 is a sectional 110

plan view on the line 6—6 of Fig. 1 illustrating the mechanism for moving the jack laterally; Fig. 7 is a sectional plan view on the line 7—7 of Fig. 1 illustrating the mechanism for rotating or oscillating the jack; Fig. 8 is a detail sectional view of the nailing device and trimming knife, and Fig. 9 is a sectional detail of the nailing device.

The machine illustrated in the drawings 10 is designed to attach the heel seat of the sole of a lasted shoe to the upper and insole by means of nails and to trim or round the projecting edge of the heel seat to conform to the shape of the last. The machine comprises 15 a nailing device and a trimming knife arranged to operate on the edge of the heel seat, the nailing device acting on the bottom of the heel seat to drive nails through the edge of the heel seat, the inturned edges 20 of the upper and insole and the trimming device acting on the projecting edge of the heel seat to trim the same. For holding the heel seat in position to be operated upon by the nailing device and trimming knife, a 25 gage is provided arranged to bear against the counter portion of the upper directly beneath the heel seat and also preferably acting to support the projecting edge of the heel seat against the cut of the trimming 30 knife. The shoe is supported with the counter portion of the upper bearing against the gage by means of a suitable shoe supporting jack, the jack being movable toward and from the gage and pressed toward the 35 gage to keep the counter portion of the shoe in contact therewith by the operator. For feeding the edge of the heel seat to the nailing device and trimming knife, means are provided for moving the jack laterally 40 to present the sides of the heel seat and for rotating the jack about the center of the heel to present the back of the heel seat to the nailing device and trimming knife. The mechanism for actuating the jack is arranged 45 to impart to the jack two lateral movements in the same direction and an intermediate rotary movement about the center of the heel. The mechanism is also arranged so that these movements are imparted 50 to the jack alternately in opposite directions, so that the edges of the heel seats of successive shoes supported upon the jack are fed to the nailing device and trimming knife in opposite directions. The jack is normally 55 pressed upwardly by means of a spring to bring the bottom of the heel seat in contact with the throat of the nailing device which acts as a stop to limit the upward movement of the jack. The movements 60 imparted to the jack are intermittent and during such movements the jack is depressed to remove the heel seat from contact with the stop formed by the throat of the nailing device. The gage which bears 65 against the counter portion of the shoe upper

is allowed to move with the jack when depressed and suitable means are provided for positively returning the gage to its original position when the jack is raised after each intermittent feeding movement. It is often 70 necessary to trim the edge of the heel seat toward the shank of the shoe farther than it is desirable to drive nails and the machine shown in the drawings is accordingly provided with means for throwing the nailing 75 device out of operation, permitting the continued operation of the jack actuating mechanism and trimming device. Means are also provided for automatically throwing the machine out of operation after the trimming 80 operation has been completed.

Referring now to the drawings in which like characters of reference indicate like parts, 1 indicates the frame of the machine supported upon a standard 2, said frame 85 and standard being of any suitable construction for supporting the operating parts. In the upper portion of the frame 1 are journaled two horizontal shafts 3 and 4 connected by intermeshing gears 5 and 6. From the shaft 4 the mechanism relating to the nailing device is operated and from the shaft 3 the mechanism for actuating the trimming knife and for actuating the jack to feed the edge of the heel seat to the nailing 95 device and trimming knife. The shaft 3 is the power shaft of the machine and is driven in any suitable manner as by means of a driving pulley 7 loosely mounted on the rear end of the shaft. A clutch collar 8 splined on the shaft 3 so as to rotate therewith but movable longitudinally thereon is forced into engagement with the clutch member 9 formed on the hub of the loose pulley 7 by means of a spring 10 surrounding the shaft 105 3 and interposed between the clutch collar 8 and the hub of gear 5. The gear 6 is loosely mounted on the shaft 4 and is normally connected thereto by means of a sliding clutch collar 11 splined on the shaft 4 110 and pressed into engagement with the hub of the gear by means of a coiled spring 12 interposed between the clutch collar and a flange at the rear end of the shaft. The clutch collar 11 is provided with an inclined projecting lug 13 which is adapted to be engaged by the inclined end 14 of an arm 15 secured to or forming a part of a shaft 16 journaled in the frame 1 and provided at the front of the machine with an operating handle 17. Normally the inclined end 14 of the arm 15 is out of the path of the lug 13 so that the gear 6 is clutched to the shaft 4 and the shaft 4 is actuated. The mechanism for actuating the nailing device 120 is driven from the shaft 4 as has been stated and by means of the construction above described the nailing device can be thrown out of operation by the manipulation of the handle 17 to bring the inclined end 14 of 125 130

the arm 15 into the path of the projection 13. The inclined end 14 of the arm 15 acting on the projection 13 forces the clutch collar 11 away from the hub of the gear 6 thereby allowing the gear 6 to revolve without actuating the shaft 4 and permitting the continued revolution of the shaft 3 from which the trimming device and the mechanism for actuating the jack are operated.

10 The nailing device shown in the drawings is of the continuous wire type and comprises a feeding device for feeding the wire the length of the nail to be cut off, a wire cutting device for cutting a nail from the wire 15 and a driver for driving the cut off nail through the heel seat, upper and insole. The wire 18 is supplied from any suitable source as from a reel supported on the frame of the machine and passes downward between feeding rolls 19 and 20. See more particularly Figs. 2 and 4. The roll 19 is loosely journaled in a bracket secured to the side of the casing 40 which forms a guide way for the driver plunger as will be described. The roll 20 is secured to the forward end of a shaft 21 journaled in the frame 1 and is intermittently actuated to feed the wire by means of a cam 22 secured to the shaft 4 and suitable connections. These connections 30 consist of a bent lever 23 pivotally supported on a shaft 24 journaled in the upper portion of the frame 1, the upper end of which lever is provided with a roll engaging the groove of cam 22 and the lower end of which lever has a pin and slot connection with an arm 25 projecting from a casing 26 mounted on the shaft 21 and forming part of a frictional driving device. This frictional driving device may conveniently be 40 of the construction shown in the patent hereinbefore referred to and it is not considered necessary to illustrate and describe such construction herein. From the feeding rolls the wire 18 passes through an opening 27 in the tubular casing 28 rigidly secured at the lower end of the casing 40. Journaled in the tubular casing 28 and free to revolve therein is a cylindrical stud 29 provided with a transverse passage way 30 of slightly 50 greater diameter than that of the wire 18 which receives the end of the wire as it is fed downward by the feeding rolls. The stud 29 projects from a block 31 provided with circular flange 32 which is engaged by 55 a segmental flanged plate 33 secured to the front portion of the casing, the engagement of the flange 32 with the segmental plate 33 serving to hold the stud 29 in position and prevent its longitudinal movement. For 60 cutting off the wire to form a nail, the stud 29 is oscillated in the tubular casing 28 to force the wire against the cutting edge formed by one side of the opening 27, as clearly shown in Fig. 9. For so oscillating 65 the stud 29 the block 31 is provided with a

projecting arm 34 which has a pin and slot connection with an arm 35 extending downwardly from shaft 24 and rigidly secured thereto. To the shaft 24 is also secured an arm 36 (see Figs. 2 and 4) which carries a roll 70 engaging the groove of a cam 37 secured to the shaft 4.

38 designates the nail driver which is carried by a plunger 39 reciprocating in a casing 40 secured to the front portion of the frame 1. The plunger 39 is actuated by means of a crank disk 41 secured to the forward end of the shaft 4 and a connecting link 42. The tubular casing 28 is provided with upper and lower openings 43 and 44 in line with the driver 38 and to the lower end of the casing 40 is secured a throat 45, the passageway in which registers with the opening 44. The oscillating movement imparted to the stud 29 in cutting off the wire 80 to form a nail is sufficient to bring the cut off nail in line with the openings 43 and 44 and the mechanism for actuating the stud 29 and driver 38 are so timed that the driver 38 descends when the cut off nail is in line with the openings 43 and 44 and forces the nail down through the throat 45 and into the heel seat.

85 The trimming device comprises a trimming knife 46 secured by means of a set screw 47 to a slide 48 mounted to reciprocate in suitable guideways on the rear portion of the casing 40. The slide 48 is reciprocated by means of a link 49 connecting the slide with a crank pin on the crank disk 50 secured to the forward end of shaft 3. The edge of the heel seat is supported against the cut of knife 46 by suitable means, preferably by means of the gage which holds 90 the heel seat in position to be operated upon by the nailing device and trimming knife.

95 The gage is indicated at 51 and consists of a plate pivoted at its rear end to the base plate of the frame 1. The gage is arranged to bear against the counter portion of the shoe upper directly beneath the heel seat and thus position the heel seat with relation to the nailing device and trimming knife and at the same time support the edge of the heel seat against the cut of the trimming 100 knife.

105 The gage is indicated at 51 and consists of a plate pivoted at its rear end to the base plate of the frame 1. The gage is arranged to bear against the counter portion of the shoe upper directly beneath the heel seat and thus position the heel seat with relation to the nailing device and trimming knife and at the same time support the edge of the heel seat against the cut of the trimming 110 knife.

115 The jack upon which the shoe is supported may be of any suitable construction and any suitable mechanism may be provided for actuating the jack to feed the edge of the heel seat to the nailing device and trimming knife. The jack which I have illustrated in the drawings and the mechanism for actuating it afford a simple and reliable construction for supporting and feeding the shoe which has been found to be highly efficient. As shown in the drawings (see more particularly Fig. 1), the jack consists of a rod or post 52 provided at its 120 upper end with a last pin for entering the 125

130

usual hole in the heel of the last, a laterally extending arm 53 secured to the rod 52 and a toe rest 54 secured to the outer end of the arm 53. The rod 52 is connected by means 5 of a universal joint with a shaft 55 journaled in a bracket 56 secured to the lower portion of the standard 2 of the machine. By reason of the universal joint the jack is free to move toward and from the gage to 10 keep the counter portion of the shoe upper in contact with the gage and also to be swung away from the gage to allow the removal and replacing of shoes upon the jack. In order to feed the edge of the heel seat 15 to the nailing and trimming devices, the jack is moved laterally to present one side of the heel seat to said devices, then rotated to present the back of the heel seat to said devices, and then moved laterally in the same direction 20 to present the other side of the heel seat to said devices. For moving the jack laterally a slide 57 is mounted to reciprocate in horizontal guideways secured to the upper portion of the standard 2. From said 25 slide an arm 58 extends laterally, which arm is provided with a slot through which the rod 52 passes, the construction being such that the rod can move toward and from the slide in the slot but has no lateral movement independent of the slide. The slide 57 is 30 reciprocated to move the jack laterally by means of a link 59 pivoted at one end to a lug projecting from the slide and at the other end to a block 60 mounted in a slide 35 in one end of a bent lever 61. The other end of the lever 61 is provided with a roll which engages a cam groove 62 in a disk 63 secured to a vertical shaft 64 journaled in the machine frame and intermittently actuated by 40 mechanism hereinafter described. The block 60 is adjusted in the slotted end of lever 61 to vary the extent of movement of slide 57 and consequently the extent of the lateral movements of the jack to correspond to different 45 sizes and styles of shoes. For locking the block 60 in adjusted position the block is provided with a sliding pin 65 which is adapted to engage any one of a series of holes 66 formed on the edge of lever 61. The pin 65 can be withdrawn from the holes 66 by means of a bent spring-pressed lever 67 pivoted to block 60, one end of which engages the pin and the other end of which extends into convenient position to be 50 grasped by the hand of the operator. The mechanism for rotating the jack comprises a segmental pinion 68 rigidly secured to a sleeve 69 through which the shaft 55 passes and with which it is connected so as to rotate therewith by means of a suitable spline, as clearly shown in Fig. 7. With the segmental pinion 68 the segmental rack 70 meshes, said rack being carried at one end of a lever 71, the other end of which is pivoted at 72 to 55 the lower portion of the standard 2, and

which is provided between its ends with a roll engaging a cam groove 73 in a disk 74 secured to the shaft 64.

The shaft 64 is intermittently actuated from the shaft 3 by means of the following 70 connections: To the shaft 3 is secured a beveled gear 75 which meshes with a similar gear on the upper end of a short vertical shaft 76 journaled in bearings in the machine frame in line with the shaft 64 (see 75 Fig. 3). To the shaft 76 is secured a disk 77 provided on its upper face with a pin 78 which is adapted to engage a notch in a notched disk 79 secured to the upper end of the short vertical shaft 80. To the lower 80 end of the shaft 80 is secured a gear 81 which meshes with a gear 82 on the vertical shaft 64. By means of this construction the notched disk 79 and through the intermeshing gears 81 and 82 the shaft 64 are intermittently rotated. The shaft 55 is splined to the sleeve 69 so as to rotate therewith and be capable of moving longitudinally therein. This construction allows the jack to be pressed upwardly to bring the bottom of the 90 shoe sole in contact with the throat 45 of the nailing device which thus acts as a stop to limit the upward movement of the jack. For pressing the jack upwardly the following mechanism may be provided: Mounted 95 in suitable guideways formed in a bracket 83 secured to the standard 2 and in the upper portion of standard 2 and base plate of frame 1 is a vertical rod 84. The lower end of the rod 84 is pivoted to a block 85 100 mounted to slide on guideways formed on a bracket 86 secured to the standard 2. Projecting from the block 85 is a yoke 87 which engages a groove formed in the upper end of shaft 55. A coiled spring 88 surrounds the rod 84 and bears at its lower end against the bracket 83 and at its upper end against a collar 89 secured to the rod. By this construction the jack is pressed upwardly to bring the bottom of the sole in contact with 110 the throat of the nailing device. It is desirable that the jack be depressed to withdraw the shoe sole from contact with the throat of the nailing device during the intermittent feeding movement of the jack. 115 The following mechanism has accordingly been provided for intermittently depressing the jack: The upper end of the rod 84 extends above the base plate of frame 1 and through an opening in the gage 51. An arm 90 secured to a rock-shaft 91 journaled on the base of the machine frame extends over the upper end of the rod 84. To the rock-shaft 91 an arm 92 is also secured, the upper end of which is provided with a roller 120 engaging the cam groove of a cam 93 secured to shaft 3. By means of this construction as the shaft 3 is rotated the rock-shaft 91 is oscillated and the arm 90 caused to intermittently depress the rod 84 and through 125 130

the block 85 and yoke 87 the shoe support and jack. To allow the gage 51 to move with the jack when the jack is depressed and for raising the gage to bring it back to its original position when the jack is raised, 5 a slide 94 is arranged to reciprocate in a guideway formed in the base of the machine frame beneath the forward end of the gage 51. For actuating the slide 94 to withdraw it from beneath the gage to allow the gage to be depressed with the jack and to move it beneath the gage to lift the gage when the jack is raised, a lever 95 is provided pivoted on the machine frame, the lower end 10 of which connects with the slide 94 by means of a pin and slot connection and the upper end of which is provided with a roll which engages the cam groove of a cam 96 secured to the shaft 3.

20 The cam grooves 62 and 73 of the disks 63 and 74 are arranged to impart to the jack two lateral movements in one direction with an intermediate rotary movement and then two lateral movements with an intermediate 25 rotary movement in the opposite direction. The movements of the jack in one direction are sufficient to present both sides and the back of the heel seat to the action of the nailing and trimming devices. Means are 30 accordingly provided for stopping the operation of the machine at the end of the lateral and rotary movements of the jack in each direction whereby the shoe previously acted upon can be removed from the jack and another shoe placed thereon, and the edges of 35 the heel seats of successive shoes supported upon the jack fed to the nailing and trimming devices in opposite directions. For so throwing the machine out of operation the 40 disk 63 is provided with two diametrically opposite lugs 97 upon its lower face which are adapted to contact with the inturned end of a vertically sliding rod 98 mounted in brackets secured to the frame of the machine. The upper end of the rod 98 is pivotally connected to an arm 99 projecting laterally from a rocking sleeve 100 journaled upon a stud projecting from the frame 1. An arm 101 provided with an inclined end 45 50 55 60 65 70 75 80 85 90 95 100 105 110 115 120 125 130

turned end of the rod 98 depresses the rod and swings the inclined end 102 of the arm 101 into the path of the lug 103, thereby throwing the machine out of operation.

For starting the machine a handle 107 is 70 secured to rod 98 and projects to the front of the machine. By means of this handle the rod 98 can be turned to disengage the inturned lower end of the rod 98 from the projection 97, thereby allowing the spring 75 104 to raise the rod and remove the inclined end 102 of arm 101 from the path of lug 103.

The operation of the machine above described may be briefly described as follows: A lasted shoe is placed in position upon the 80 jack and the jack pressed toward the gage to bring the counter portion of the upper against the gage 51, the jack at this time being in a position at right angles to the position shown in Fig. 1. The handle 17 is 85 turned to bring the inclined end 14 of the arm 15 into the path of projection 13 on the clutch collar 11 and the handle 107 is operated to throw the machine into operation.

By means of the mechanism above described the jack 52 will be moved laterally and the trimming knife operated to trim the side of the heel seat. When the point on the heel seat is reached at which it is desired to begin the driving of the nails, the handle 17 is operated to remove the inclined end 14 of the arm 15 from the path of lug 13 to thereby throw the nailing devices into operation. When the back of the heel seat is reached the jack is rotated to present the back of the heel seat to the nailing and trimming devices and thereafter the jack is moved laterally to present the other edge of the heel seat to said devices. When the point on the heel seat is reached at which it is desired to discontinue the driving of the nails, the handle 17 is again operated to cause the inclined end 14 of the arm 15 to engage the lug 13 to throw the nailing devices out of operation. At the end of the lateral movement of the jack the disk 63 will have completed a half revolution and one of the lugs 97 will engage the inturned end of the rod 98 and depress the rod to swing the inclined end 102 of the arm 101 into the path of lug 103 and stop the operation of the machine. At each intermittent feeding movement of the jack the arm 90 acting on the upper end of rod 84 will depress the jack to withdraw the shoe sole from contact with the throat of the nailing devices during the feeding movement. During the downward movement of the jack the slide 94 is withdrawn from beneath the gage 51 to allow the gage to move with the jack and during the upward movement of the jack the gage is positively returned to its original position by the movement of the slide beneath the gage. The shoe which has been operated upon is now removed 130

from the jack and another shoe placed thereon, and the machine thrown into operation as before, the operation above described being repeated, except that the edge of the heel seat is fed to the nailing and trimming devices in the opposite direction.

The machine shown in the drawings and above described is provided with two tools which operate upon the edge of the heel seat, one tool acting to trim the edge and the other to attach the edge to the lasted upper and insole. It will be understood, however, that certain features of my invention are not limited to the particular type 10 of tool or tools which operate on the edge of the sole nor are they limited to tools arranged to act on any particular part of the sole. Certain features of my invention are 15 equally applicable to other types of shoe machines which are adapted to operate upon the soles of shoes, and where in the claims I specify a tool arranged to act upon the edge of the shoe sole I do not intend to limit myself to any particular form of tool but intend to include any tool arranged to operate 20 at or near the edge of any part of the sole portion of a shoe.

Having thus described my invention, I claim as new and desire to secure by Letters 30 Patent of the United States.

1. A sole machine, having, in combination, a tool arranged to operate on the edge of a shoe sole, a jack arranged to support a shoe in position to be operated upon by the tool, 35 means for actuating the jack to feed the edges of the soles of shoes supported on the jack alternately in opposite directions and means acting automatically to stop the jack at the end of its movement in each direction 40 and maintain the jack in stopped position to permit the removal of the shoe operated upon and the substitution of a shoe to be operated on whereby the sole edges of successive shoes supported on the jack are 45 fed to the tool in opposite directions, substantially as described.

2. A sole machine, having, in combination, a tool arranged to operate on the edge of a shoe sole, a gage arranged to bear against the shoe and position the sole with relation to the tool, a jack movable toward and from the gage arranged to support a shoe in contact with the gage, a shaft for supporting the jack, a universal joint between the shaft 55 and jack, means for rotating the shaft and means for moving the jack laterally, substantially as described.

3. A sole machine, having, in combination, a tool arranged to operate on the edge of a shoe sole, a gage arranged to bear against the shoe and position the sole with relation to the tool, a jack movable toward and from the gage arranged to support a shoe in contact with the gage, a shaft for supporting 60 the jack, a universal joint between the shaft

and jack, means for rotating the shaft, and means for moving the jack laterally having provision for adjustment to vary the extent of such lateral movements, substantially as described.

4. A sole machine, having, in combination, a tool arranged to operate on the edge of a shoe sole, a trimming device for trimming the edge of the sole, a jack arranged to support a shoe with the sole in position to be operated upon by the tool and trimming device, means for actuating the jack to feed the edge of the sole to the tool and trimming device, and means for throwing the tool out of operation permitting a continued operation of the trimming device and jack actuating means, substantially as described.

5. A sole machine, having, in combination, a nailing device, a trimming device, a jack arranged to support a shoe with the sole in position to be acted upon by said devices, means for actuating said devices, means for actuating the jack to feed the sole edge to said devices and space the nails driven by the nailing device, and means for throwing the nailing device out of operation permitting a continued operation of the trimming device and jack actuating means, substantially as described.

6. A sole machine, having, in combination, a tool arranged to act on the edge of a shoe sole, a jack arranged to support a shoe with the sole in position to be acted upon by the tool, and to feed the sole edge to the continued action of the tool, a stop, means acting on the jack to press the bottom of the sole against the stop, means for actuating the jack to intermittently withdraw the sole from said stop, and to feed the sole edge to the tool, substantially as described.

7. A sole machine, having, in combination, a tool arranged to act on the edge of a shoe sole, a gage arranged to bear against the shoe and position the sole with relation to the tool, a jack arranged to support a shoe in contact with the gage, and to feed the shoe sole to the continued action of the tool, a stop, means acting on the jack to press the bottom of the sole against the stop, means for actuating the jack to intermittently withdraw the sole from said stop and to feed the sole edge of the tool, said gage being movable with the jack toward and from the stop, substantially as described.

8. A sole machine, having, in combination, a tool arranged to act on the edge of a shoe sole, a gage arranged to bear against the shoe and position the sole with relation to the tool, a jack arranged to support a shoe in contact with the gage and to feed the shoe sole to the continued action of the tool, a stop, means acting on the jack to press the bottom of the sole against the stop, means for actuating the jack to intermittently withdraw the sole from said stop and

- to feed the sole edge to the tool, means for allowing said gage to move with the jack from the stop, and means independent of the jack for moving the gage with the jack 5 toward the stop, substantially as described.
9. A sole machine, having, in combination, a nailing device including a throat having a nail passage, a trimming device, a jack arranged to support a shoe with the heel seat in position to be operated upon by said devices, and to feed the shoe sole to the continued action of said devices, means acting on the jack to press the bottom of the heel seat against the throat of the nailing device, and means for actuating the jack to intermittently withdraw the heel seat from said throat and feed the edge of the heel seat to the nailing and trimming devices, substantially as described.
10. A sole machine, having, in combination, a nailing device, a trimming device, a jack arranged to support a shoe with the sole in position to be acted upon by said devices, a stop, means acting on the jack to press the bottom of the sole against the stop, and means for actuating the jack to intermittently withdraw the sole from said stop, and to feed the sole edge to said devices and space the nails driven by the nailing device, substantially as described.
11. A sole machine, having, in combination, a nailing device, a trimming device, a jack arranged to support a shoe with the sole in position to be acted upon by said devices, and means for actuating the jack to intermittently feed the sole edge to said devices and space the nails driven by the nailing device, substantially as described.
12. A sole machine, having, in combination, a vibrating trimming knife, means for actuating said knife, a jack arranged to support a shoe in position to be operated upon by said trimming knife, and means for actuating the jack to intermittently feed the edge of the shoe sole to the trimming knife, substantially as described.
13. A sole machine, having, in combination, a nailing device, a jack arranged to support a shoe with the heel seat in position to be acted upon by the nailing device, a stop, means acting on the jack to press the bottom of the sole against the stop, means for actuating the jack to intermittently withdraw the sole from said stop, and means for feeding the shoe to present the edge of the heel seat to the nailing device and space the nails driven thereby, substantially as described.
14. A sole machine, having, in combination, a nailing device, a jack arranged to support a shoe with the heel seat in position to be acted upon by the nailing device, and means for feeding the shoe to present successive portions of the edge of the heel seat to the nailing device and space the nails driven
- thereby including means for moving the jack laterally while the nails are being driven along the sides of the heel seat and additional means for rotating the jack while the nails are being driven around the rear edge of the heel seat, substantially as described.
15. A sole machine, having, in combination, a nailing device, a jack arranged to support a shoe with the heel seat in position to be acted upon by the nailing device, a gage for determining the position of the shoe with relation to the nailing device, said jack being movable toward and from the gage, means for feeding the shoe to present the side edges of the heel seat to the nailing device and space the nails driven thereby, and additional means for rotating the jack to space the nails around the rear edge of the heel seat, substantially as described.
16. A sole machine, having, in combination, a tool arranged to operate on the edge of the heel seat of a shoe sole, a jack arranged to support a shoe with the heel seat in position to be operated upon by the tool, means for moving the jack laterally while the tool is acting along the sides of the heel seat and additional means for rotating the jack while the tool is acting on the rear edge of the heel seat, substantially as described.
17. A sole machine, having, in combination, a nailing device, a jack arranged to support a shoe with the heel seat in position to be acted upon by the nailing device and means for feeding the shoe to present the edge of the heel seat to the nailing device and space the nails driven thereby, said means comprising means for moving the jack laterally and additional means for rotating the jack, substantially as described.
18. A sole machine, having, in combination, a tool arranged to operate on the edge of the heel seat of a shoe sole, a gage arranged to bear against the counter portion of a shoe upper and position the heel seat with relation to the tool, a jack arranged to support a shoe with the counter portion of the upper bearing against said gage, means for feeding the shoe to present the side edges of the heel seat to the tool, and additional means for rotating the jack to present the rear edge of the heel seat to the tool, substantially as described.
19. A sole machine, having, in combination, a vibrating trimming knife, means for actuating said knife, a jack arranged to support a shoe with the sole in position to be acted upon by said knife, means for supporting the edge of the sole against the cut of the knife, and means for actuating the jack to present successive portions of the sole edge to the knife, substantially as described.
20. A sole machine having, in combination, a tool arranged to operate on the edge of a shoe sole, a support for the shoe, means

for actuating the support to feed the edges of the soles of shoes on the support alternately in opposite directions, and means acting automatically to stop the support at the end of its movement in each direction and maintain the support in stopped position to permit the removal of the shoe operated upon and the insertion of a shoe to be operated on, whereby the sole edges of successive shoes placed on the support are fed to the tool in opposite directions, substantially as described.

21. A sole machine having, in combination, a tool arranged to operate on the edge of a shoe sole, a shoe support, means for actuating the support to feed the edge of a shoe sole to the tool arranged to automatically reverse the direction of movement of the support and means acting automatically to stop the support at the end of its movement in each direction and maintain the support in stopped position to permit the removal of the shoe operated upon and the insertion of a shoe to be operated on whereby the sole edges of successive shoes placed on the support are fed to the tool in opposite directions, substantially as described.

22. A sole machine having, in combination, a tool, mechanism for feeding the edge

of a shoe sole past the tool having provision for automatic reversal of its operation and means acting automatically to stop the feed at the end of the feeding movement in each direction and maintain the feed in stopped position to permit the removal of the shoe operated upon and the insertion of a shoe to be operated on whereby the sole edges of successive shoes are fed to the tool in opposite directions, substantially as described.

23. A sole machine having, in combination, a tool, mechanism for feeding the edge of a shoe sole past the tool in opposite directions, and means acting automatically to stop the feed at the end of the feeding movement in each direction and maintain the feed in stopped position to permit the removal of the shoe operated upon and the insertion of a shoe to be operated on whereby the sole edges of successive shoes are fed to the tool in opposite directions, substantially as described.

In testimony whereof I affix my signature, in presence of two witnesses.

ERASTUS EDWIN WINKLEY.
